H. Woodward

UNITED STATES PATENT OFFICE.

MAE NOEL, OF WASHINGTON, DISTRICT OF COLUMBIA.

PLAITING APPARATUS.

Application filed May 11, 1921. Serial No. 468,702.

To all whom it may concern:

Be it known that I, MAE NOEL, a citizen of the United States, residing at Washington, in the District of Columbia, have invented certain new and useful Improvements in Plaiting Apparatus, of which the following is a specification.

The invention has for its object the improvement of methods and apparatus of plaiting or forming creased patterns in cloth, especially those which involve two pattern sheets having duplicate intermeshing creases between which patterns the goods is laid and pressed. It has been customary heretofore to roll the pattern sheets with the interposed goods upon a drum or roller, this being ordinarily accomplished by laying the patterns upon a large table and after adjustment in proper relation with the goods therebetween, a strong man has been employed to roll them upon the drum. This was done by laying the drum upon the end of the patterns, securing the pattern to the drum and rolling it across them, the operator crawling upon the table and bearing as heavily as possible upon the roll as he pushed it along. The parts being wound, the drum and materials thereon are inserted in an oven and steamed, to cause the goods to permanently retain the pattern impressed.

The purpose of my invention is to obviate the necessity for the arduous work of rolling the pattern on the drum as described, and permit the adjustment of the patterns to the goods and its compression with greater facility and ease, enabling a woman to do the work instead of a man, as the hiring of a man is an excessive expense in this work, plaiting shops being ordinarily conducted by women.

It is a further purpose to provide a drum of light weight which may be readily handled by women and yet possess the necessary rigidity for the uses contemplated by my invention.

It is an object also to present a machine for this purpose which will be simple to operate, and involve few parts, all of which are of a character to minimize liability of derangement or breakage.

A further aim is to so construct the ma-

chine that it may be readily operated in a small space.

Another aim is to provide means to maintain high pressure upon the patterns and goods as engaged upon the drum, without requiring strength in the drum to maintain this pressure in the ordinary way.

Additional objects, advantages and features of invention reside in the construction, combination and arrangement of parts, as will be understood from the following description and accompanying drawings, wherein,

Figure 1 is an isometric perspective of a machine constructed in accordance with my invention;

Figure 2 is a fragmentary side elevation with parts removed to show the form of the guide slots;

Figure 3 is an enlarged fragmentary detail of the drum and platen roll in operation upon patterns and goods;

Figure 4 is a fragmentary front elevation of the machine;

Figure 5 is a fragmentary longitudinal section of the drum;

Figure 6 is a detail of the winding shaft guide bearing;

Fig. 7 is a detail of an adjustable support for the mechanism; Fig. 8 is a fragmentary illustration showing a spring for bearing the drum upon the roll; Fig. 9 is an enlarged detail of the pattern and goods as fed to the roll, and illustrated in Fig. 3.

There is illustrated a machine which includes a table part 10 which may be of any suitable length, supported, if desired, at one end by the frame standards 11 of the machine, the standards being provided with brackets 12 for this purpose.

The machine is of identical construction at each side.

Between the standards there is mounted a platen roll 13 having its shaft or trunnions 14 permanently journalled in the standards. This roll is of a size to bring its periphery at the upper side on a level with the top of the table 10, and the table top is projected and undercut to lie close to and conform to the shape of the roll, as indicated at 15 in Figure 3.

The standards 11 are provided with ver-

tical slots 16 therein alined with the axis of the roll 13, and having vertically slidable and revoluble therein spool-shaped guide bearings blocks 17 provided with rectangular openings 18 therethrough. These blocks receive slidably therethrough a rectangular drum-operating shaft 19 having hand cranks 20 at the ends. The drum 21 consists of a number of circular heads 22 which 5 may be of wood having a multiplicity of narrow slats 23 secured to their peripheries in close spaced parallel relation. To facilitate engagement of the shaft 19 in the drum the latter may be provided with a rectangular tube 24 suitably mounted in the heads 10 22 and flared at the outer ends. This will also reduce liability of twisting of the drum by the torque in case it is desired to operate the drum by one crank only.

15 20 The tube 24 may be mounted in flange plates 25 secured to respective heads 22.

On a level slightly below the top of the drum 21 when resting upon the roll 13 the slots 16 are enlarged as at 26 in Figure 2, 25 providing enlarged vertical slots 27, in which there is loosely revoluble a weight-roll 28, ordinarily in the form of a section of iron pipe. This is of a length to project a distance outwardly through each of 30 the standards 11, and if desired, may be provided with collars 29 to assist in its adjustment and retention in proper medial position in the frame. The slots 27 are provided at their upper ends with lateral extensions 35 27' with a slight dip, providing shoulders 31, so that the roll 28 may be lifted and set thereon and thus supported out of the way while introducing or removing a drum.

The roll 21 is of a length less than the 40 space between the standards, to permit its ready introduction and removal to and from position in the machine, and has been customarily made about six inches in diameter, the platen roll being of the same diameter, 45 although this is not essential. The roll 28 has been formed of two-inch pipe.

If desired, the shaft 19 may be provided 50 with removable pins 30 to limit its insertion through the guide blocks 17, thereby obviating liability of adjustment of the cranks so as to strike the ends of the roll 28.

To permit adjustment of the pressure upon the drum 28, when the weight of the roll 28 is not sufficient for the character of 55 work to be done, I have provided an endless belt 32 at each end of the roll, hanging upon its projecting parts, and pendant therefrom. In the lower part of this belt there is rested a flanged roller from which 60 there is suspended a hook 33 upon which various sized weights 34 may be hung.

In the use of the machine, the roll 28 being lifted onto the shoulders 31, and a drum 21 adjusted in position with the shaft 19 65 inserted properly, patterns 35 are laid upon

the table with a paper bed sheet 36 thereunder of equal width, but greater length. The sheet 36 is started upon the drum so as to form three or four layers thereon before any of the pattern is engaged. The goods 70 35 having been adjusted properly between the patterns and the patterns properly intermeshed and laid on the sheet 36, the lead tongue 37 of the patterns is inserted under the roll so as to begin the take-up of the pattern. At this point the roll 28 is lifted from the shoulders 31 and lowered into the wide slot 27 so as to rest upon the upper side of the drum, and whatever weights 34 that may be necessary are placed upon the hooks 33. Elongated weight elements 38 which may be termed "floats" are also adjusted upon the tops of the patterns, arranged longitudinally of the table, so as to bear upon and hold the patterns and goods 80 thereunder in proper relation during the subsequent operations. Two of these floats are ordinarily sufficient. They are planiform on their under sides and have their forward ends shaped with curved rearwardly inclined faces so that they may extend partly forward under the drum, and are shaped, so that the floats may bear against the drum without blocking it, being borne thereagainst by the patterns as they slide forward. When the complete patterns and bed sheet are engaged upon the drum, bands are fed around the drum and tied so as to hold the parts securely thereon, and the drum lifted out on to the table to permit removal of the shaft 19. The drum with the wound patterns and interposed goods thereon is then introduced into a steam chest in a customary way to set the goods 90 in the form in which it is held by the patterns 35.

The machine is adapted to be manufactured at a low cost, and installed at a minimum of expense, and is adapted to ready use by inexperienced operatives. When the machine is not being used, the table part may be put to general uses of shops doing varied work, without liability of impairment of the machine, the machine parts then occupying little additional room.

By the use of the roll 28 to apply pressure, instead of applying pressure to the shafts of the drum, the bearing of the roll 28 equally upon the drum throughout its length will remove liability of the resilience of the patterns and goods distorting the drum by raising its middle portion, which would prevent proper compressing and creasing of the goods equally at all parts. This makes it possible to use a drum of extremely light construction, which can be readily handled by young girls or others of moderate physical strength.

It should be noted that the platen roll is virtually a continuation of the table and the 100

roll may be omitted and the drum rotated directly upon the table, which would thus become a platen. The roll is utilized to lessen friction.

5 An opening 39 is formed from the slots 27 at their upper ends through the inner edges of the standards, so that after the weight-roll is lifted into the recess 27' the drum and its shaft may be lifted out of the 10 standards in the direction of the table, permitting subsequent removal of the shaft 19 whenever most convenient, and also allowing insertion of the shaft similarly. The empty drum may be put in the machine in 15 the corresponding reverse way, the shaft being inserted, the members 17 put in place and the shaft and parts thereon lifted into position through the opening 39. The shaft 19 may be made in two sections if desired, 20 as indicated in Figure 4, and the sections inserted in the drum after it is adjusted over the platen roll 13.

If desired, in order to make the device 25 readily adjustable to work-benches, without requiring the table part to be a part of the equipment sold by manufacturers, the height of the machine may be made adjustable as indicated in Figure 7. Therein the standards 11' are each made with a separate foot 30 piece 11^a receiving the upper parts of the standards slidably therein, and secured in adjusted positions by bolts and nuts 40.

Instead of a weight, a spring device may 35 be used to apply extra pressure to the drum, as indicated in Figure 8, where an eye bolt 41 is mounted in the foot piece of the standard, to which a helical spring 42 is anchored, the other end of which is engaged by the hook yoke 33 before described.

40 In actual practice, with certain jobs, as, where a very light goods is to be plaited, and with certain patterns, the use of extra weight, or any weight other than that of the drum itself, may be dispensed with. It 45 should be noted also, that the belt 32 may be engaged directly upon the shaft 19 instead of the weight-roll 28.

The patterns 35 referred to are customarily made of stiff paper in long sheets which 50 have been crimped or scored and folded in the form which it is desired to impart to the goods. Two such patterns are employed, which are first stretched out one at a time, the goods being laid on one and the other 55 pattern then laid over the goods, the crease lines of the patterns being alined so that by pressing the patterns longitudinally in opposite directions so as to shorten them, they may be pressed into the approximate 60 form which the finished pleat shall have, the alternate bends of one pattern lying closely within like bends of the other and forcing the goods into a similar form, making plaits. The whole body of patterns and 65 interposed goods is then wound upon the

machine, the outer windings confining and pressing upon those within, holding the goods so that the plaits may become set accurately.

What is claimed:

1. In a plaiting machine of the character described, the combination of a table element, a roll in close relation thereto, a winding drum mounted in yielding bearing upon the roll, means to secure patterns and fabric 75 to the drum to feed thereto from the table element pattern sheets shaped to fold in intermeshed relation and coact to hold interposed goods to a desired shape when wound upon the drum, and means to rotate the drum.

2. A machine for the purpose described comprising a frame, a platen roll revoluble in the frame, a removable drum revoluble thereover and movable upwardly, means to rotate the drum, and a rigid weight roll mounted to rest against the drum and for movement bodily therewith.

3. A machine for the purposes described comprising a frame, a platen roll mounted 90 therein, a removable drum revoluble thereover and movable upwardly, means to rotate the drum, a weight roll mounted to rest upon the drum and projecting a distance therebeyond at each end, and weight carrying means mounted thereon disengageable by relative longitudinal movement with respect to the weight roll.

4. A machine for the purpose described comprising a frame, a platen roll mounted 100 therein, a removable drum revoluble thereover and movable upwardly, means to rotate the drum, a weight roll mounted to rest upon the drum and projecting a distance therebeyond at each end, weight carrying means 105 removably mounted thereon, and means to support the weight roll in elevated position.

5. A machine for the purposes described comprising a frame, a platen roll therein, said frame having slots formed in each side 110 thereof radial with respect to the roll, a drum on the roll having axial parts extended through the slots, a weight roll to rest upon the drum having parts extended through the slots, weight elements engaged therewith, and means to support the weight roll spaced 115 above the drum at times.

6. A machine of the character described comprising a frame, a platen element, a drum revoluble thereover, said frame having alined slots formed in each side thereof, said drum having an angular axial passage 120 therein, a corresponding angular shaft insertable through the slots for engagement in the passage rotating means on the shaft, and means to apply weight to the drum.

7. In a plaiting machine, the combination of a table, patterns slidable thereon, a vertically movable drum revoluble closely thereover, means to rotate the drum, and 130

transversely spaced members adapted to rest slidingly upon the patterns shaped to fit partly under the drum and extending from the drum longitudinally of the table a considerable distance.

8. A machine for plaiting comprising a platen element, a drum revoluble thereover positioned to rest on the platen and mounted for vertical movement, means to rotate the drum, flexible pattern devices windable upon

the drum and means to connect the patterns for winding to the drum said patterns being shaped to coact and hold interposed goods to a desired shape when compressed.

In testimony whereof I have affixed my ¹⁵ signature in presence of two witnesses.
